UNITED STATES PATENT OFFICE.

JOHN F. O'CONNOR, OF CHICAGO, ILLINOIS, ASSIGNOR TO WILLIAM H. MINER, OF CHAZY, NEW YORK.

TWO-PART HORIZONTAL YOKE.

1,278,373.

Specification of Letters Patent. Patented Sept. 10, 1918.

Application filed January 6, 1917. Serial No. 140,881.

To all whom it may concern:

Be it known that I, JOHN F. O'CONNOR, a citizen of the United States, residing at Chicago, in the county of Cook and State 5 of Illinois, have invented a certain new and useful Improvement in Two-Part Horizontal Yokes, of which the following is a full, clear, concise, and exact description, reference being had to the accompanying drawings, forming a part of this specification.

This invention relates to improvements in two-part horizontal yokes.

The object of the invention is to provide a horizontal yoke for railway draft riggings 15 wherein the yoke is formed of two members detachably connected to the draw bar and to each other, the connections being such that, when the yoke parts and draw bar are assembled, separation of the yoke parts is prevented.

In the drawing forming a part of this specification, Figure 1 is a side elevation of a portion of a draw bar and my improved yoke assembled therewith. Fig. 2 is a vertical sectional view of the structure illustrated in Fig. 1 and taken on the line 2—2 thereof. Fig. 3 is a detail perspective view of the forward end of one of the yoke members employed in the construction illustrated 25 in Fig. 1. Fig. 4 is a view similar to Fig. 1, but illustrating a different embodiment of the invention. And Fig. 5 is a vertical sectional view of the structure illustrated in Fig. 4 and taken on the line 5—5 thereof.

Referring to the construction illustrated in Figs. 1, 2 and 3, 10 denotes the shank of a draw bar having the usual standard butt 11, the latter being formed with upper and lower shoulders 12 and 13. The improved 35 yoke, as shown, comprises two counterpart members 14—14 each of which is in the form of a loop with the arms thereof extending horizontally in the same plane. The arms of each member are connected at the rear by a transverse portion 15 and at the front by vertically extending walls 16—16, the latter being connected by a transversely extending wall 17. Each of the walls 17, at its forward 45 edge, is provided with an inturned transversely extending gib or shoulder 18 adapted to coöperate with the corresponding shoulder 12 or 13 of the draw bar butt. The yoke 50

members 14—14 are detachably connected at their forward ends by means of a hinge joint, the latter comprising an offset flange 19 on one yoke member, the flange 19 being provided with an inwardly extending, substantially circular lug 20. The corresponding portion of the other yoke member is provided with an outwardly extending, substantially circular lug 21 and a curved rib or flange 22 substantially concentric with the lug 21, thus forming a circular groove 23 between the lug 21 and rib 22. The yoke members are made counterparts so that the lug 21 of one member will coöperate with the offset flange 19 and lug 20 of the other member and vice versa.

The yoke members 14—14 are assembled by first placing the same at an angle to each other and engaging the hinge joint, as above described. The two yoke members are then swung into parallel as illustrated in Fig. 1 and may be detachably connected at their rear end by means of a cotter 24. In this condition, the gibs 18 will be brought into engagement with the butt shoulders 12 and 13 and the yoke members prevented from either vertical or longitudinal relative movement.

In the construction illustrated in Figs. 4 and 5, the two yoke members 114—114 are provided at their front ends with transversely extending walls 117—117 which also act as gibs or shoulders to engage the shoulders of the draw bar butt. Furthermore, the yoke members 114 are each provided on one side with a longitudinally arranged curved flange 40 and on the opposite side with a corresponding longitudinally extending rib 41, the rib 41 of one yoke member engaging with the curved flange 40 of the other yoke member when the yoke members are moved longitudinally relatively to each other.

I claim:

As an article of manufacture, a horizontal yoke for railway draft riggings adapted to be assembled with a standard shouldered draw bar, said horizontal yoke comprising two horizontally extending loop-shaped members one above the other, each of said members having a transversely extending section adapted to fit over the draw bar shank and engage with the adjacent draw

bar shoulder, the upper member being thereby adapted to be supported from the draw bar, said members having integral coöperating interfitting projections and recesses for detachably connecting the same by relative movement between the members, said means, when the parts are assembled, preventing

vertical separation and thereby adapted to retain said members in operative relation with the draw bar.

In witness that I claim the foregoing I have hereunto subscribed my name this 30th day of Dec., 1916.

JOHN F. O'CONNOR.
